UNITED STATES PATENT OFFICE.

GUSTAF JOHNSON AND NELSON J. RUSSELL, OF ROCKFORD, ILLINOIS.

PUMP.

1,022,556.

Specification of Letters Patent.

Patented Apr. 9, 1912.

Application filed March 17, 1911. Serial No. 614,999.

To all whom it may concern:

Be it known that we, GUSTAF JOHNSON and NELSON J. RUSSELL, citizens of the United States, residing at Rockford, in the 5 county of Winnebago and State of Illinois, have invented certain new and useful Improvements in Pumps, of which the following is a specification.

This invention relates to improvements 10 in pumps, and it consists in certain peculiarities of the construction, novel arrangement, and operation of the various parts thereof as will be hereinafter more fully set forth and specifically claimed.

15 The principal object of the invention is to provide a pump which shall be simple and inexpensive in construction, strong, durable, and effective in operation.

Other objects and advantages of the invention will be disclosed in the subjoined description and explanation.

In order to enable others skilled in the art to which the invention pertains, to make and use the same, we will now proceed to describe it referring to the accompanying drawing in which—

Figure 1, is a vertical sectional view through the center of a pump embodying the invention. Fig. 2, is a view partly in section and partly in elevation of the pump, showing the plunger or piston thereof and some of the valves in a different position from that illustrated in Fig. 1, and Fig. 3, is a view of one of the valve seats showing it 35 detached from the casing.

Like numerals of reference refer to corresponding parts throughout the different views of the drawing.

The reference numeral 28, designates the 40 piston or plunger operating rod, to the upper portion of which rod power may be applied in any suitable manner for operating the pump. The lower portion of the rod 28, is pivotally secured to a projection 29, on 45 the inner surface of the lower portion of the plunger or piston 30, of the pump. This piston or plunger as is clearly shown in Figs. 1, and 2, of the drawing, is located in an upright cylinder 31, thereof, which cylinder may be supported in any suitable manner, and has at its upper end an annular recess 32, to receive a metal packing ring 33, which fits snugly around the plunger or piston 30, and has at its upper portion an annular flange 34, to rest on the top of the plunger cylinder, the upper end of which

cylinder is externally screw threaded to engage the internally screw threaded portion of the sleeve 35, which has an inwardly extended flange 36, located at about its middle 60 to fit snugly around the piston 30, and to rest on the upper surface of the flange 34, of said packing. The upper portion of the sleeve 35, is externally screw threaded to engage the screw threads of a cap 37, which 65 surrounds the upper portion of the piston 30, and forms a closure for the space 38, between the upper portion of said cap and the flange 36, on the sleeve 35, thus forming a sealed compartment for holding lubricating 70 or other material for the piston 30, and its cylinder, and at the same time providing means for preventing the passage of air between said cylinder and the piston therein. The lower portion of the cylinder 31, 75 is provided with a horizontally disposed opening 39, which has communication through a tubular projection 40, with a section 41, of the valve casing of the pump. This casing is composed of a series of sections 80 to permit of the easy assemblage of the valves and springs which actuate the same, and is herein shown, as comprising the tubular section 41, having its upper and lower ends screw threaded, the former end 85 to engage external screw threads on the valve seat 42, and the latter to engage similar screw threads on the valve seat 43, which latter valve seat is formed integral with a section 44, of the casing, which latter section 90 has at its lower end internal screw threads to engage a valve seat 45, the lower portion of which engages the lowermost section 46, of the valve casing which section has an inlet opening 47, to which may be 95 connected by means of a suitable coupling 48, a pipe, not shown, leading from a source of supply.

Engaging the upper portion of the valve seat 42, is a section 51, of the valve casing 100 which has formed integral with its upper portion an annular valve seat 52, which has its upper portion externally screw threaded to engage a cap 53, which is provided with a centrally disposed tubular projection 54, to 105 which is connected one end of a discharge pipe 55, which may lead to a suitable point of discharge. Each of the valve seats 42, 43, 45, and 52, is annular in shape, and is provided at its upper portion with an inwardly 110 and downwardly beveled surface 56, to receive the correspondingly shaped edges of

the valves which rest on said seats. Each of the valve seats, whether made integral with sections of the valve casing, or separately therefrom, is substantially of the same construction, and each has a diametrically disposed member 57, against which the upper portions of the springs 58, which actuate said valves in one direction will rest. As is clearly shown in Fig. 1, of the drawing, each of the valve seats 43, and 45, is provided with a disk valve 59, each of which has a centrally located stem 60, projecting upwardly and downwardly therefrom, the downward portion of each stem being located in the central opening 61, of the member 57, of its valve seat, which provide guides or bearings for said stems. Each of the valve seats 42, and 53, which are located above the channel of communication between the valve casing 41, and the cylinder 31, is also provided with a disk valve 59, of the same construction as those just described. Surrounding a portion of each of the valves is a spring 58, which rests at one of its ends on the upper surface of a valve and at its other end against the member 57, of the valve seats, except in the case of the uppermost spring, which rests at its upper portion against the cap 53, of the valve casing.

From the foregoing and by reference to the drawing, it will be clearly seen, and readily understood, that when power is ap-

plied to the operating rod 28, the piston 30, will be reciprocated, thus causing the alternate operation of the valves 59, a pair of each of which is located above and below the port leading from the valve casing to the plunger cylinder. In this operation it is apparent that suction will be created at the inlet opening 47, and that liquid or fluid will be drawn into the valve casing, and forced therefrom through the discharge pipe 55, to the desired point of discharge.

Having thus fully described our invention what we claim as new and desire to secure by Letters-Patent is—

A pump including a valved casing provided with an inlet and an outlet, a pump cylinder communicating with said casing between the ends thereof and having at its upper end an annular recess, a packing ring fitted in said recess, a sleeve fitted on the upper portion of said cylinder and having an inwardly extended flange to rest on said packing ring, a cap secured on the upper portion of said sleeve, a plunger mounted in said cylinder and extended through said sleeve and cap, and means to operate said plunger.

GUSTAF JOHNSON.
NELSON J. RUSSELL.
